MANUFACTURE OF FULL-FASHIONED HO- SIERY ON FLAT KNITTING MACHINES

John S. Chipman, Easton, Pa., assignor to Chip-
man Knitting Mills, a corporation of Pennsyl-
vania

Application January 21, 1937, Serial No. 121,490

4 Claims. (Cl. 66—109)

The present invention relates to improvements in the manufacture of full-fashioned hosiery on flat knitting machines, and more particularly to a novel and improved knockover element motion which is well adapted for use in machines of this description, to produce a relatively shorter and tighter inner selvage loop formed by a reinforcing or splicing yarn in the knitting of reinforced portions of the stocking blank.

10 In the knitting of fabric on flat full-fashioned type machines, as well known in this art, the loops forming the selvage edges tend to be somewhat more loosely knitted than the loops forming the body fabric wales. This condition results 15 from the fact that the yarn extending from the feeding carrier when reversal takes place, is anchored in the fabric, which is at this time located considerably below the bottom line of the sinkers, so that a somewhat greater amount 20 of yarn is utilized in the formation of the first or selvage loop than that measured against the needles knitting the body portion of the fabric by the subsequent operation of the sinkers. While in the knitting of ordinary fabric, the 25 somewhat looser selvage loops formed as above described, are probably of advantage to prevent the formation of an excessively tight and non-elastic selvage, it has been found that inner selvage edges formed in this manner by supplemental or reinforcing yarns, being somewhat 30 looser than the loops formed by the main knitting yarn on which they are superimposed, serve no useful purpose, and may in fact tend to detract from the appearance of the finished stocking. While in the knitting of ordinary hosiery, splicing or reinforcing threads appear on the 35 inside of the finished stocking, and are, therefore, to a certain extent concealed, it has been found in the knitting of finer grades of full-fashioned hosiery on fine gauge machines, that the presence of the relatively uneven demarcation line thus formed, is very noticeable. Particularly in the knitting of what is known as inside-out hosiery, that is, hosiery in which the normal 40 face of the stocking is worn outside, and in which the reinforcing threads may appear on the outside of the finished stocking, the presence of a loose thread forming the inner selvage loops tends to give a slipshod, sleazy appearance to 45 the entire stocking.

In accordance with the present invention, it is proposed to relatively shorten the loops of reinforcing yarn forming the inner selvage edges of the reinforced portions of the stocking, so that 50 a firm, straight appearing selvage edge of the

reinforcing yarn is secured which is tightly knitted into the body of the stocking to produce a clean cut and not too conspicuous line of demarcation between the reinforced and adjacent non-reinforced portions of the stocking.

Further in accordance with the present invention, to produce the tight inner selvages above described, applicant has provided a novel and improved knockover element motion which is constructed and arranged to raise the knockover elements from the normal knockover position to a point closely adjacent the under side of the sinkers subsequent to the operation of the sinkers to measure yarn and prior to the advance of the dividers, so that the length of selvage 15 yarn extending between the previously knitted fabric and the last active needle and forming a part of the needle loop kinked against the needle by the subsequent advance of the adjoining divider, is relatively shortened, to insure the formation of a tight selvage edge.

The several features of the invention consist also in the devices, combinations and arrangement of parts hereinafter described and claimed which together with the advantages to be obtained thereby will be readily understood by one skilled in the art from the following description taken in connection with the accompanying drawing, in which Fig. 1 is a sectional view of a full-fashioned knitting machine illustrating particularly applicant's improved knockover element motion, only so much of the machine being disclosed as is believed necessary to show the connection of the present invention therewith; Fig. 2 is an enlarged detail view showing the position of the needles, webholders, sinkers and dividers at the completion of the yarn measuring operation, but prior to the advance of the dividers; Fig. 3 is a view similar to Fig. 2, showing the knockover elements in the raised position and with the dividers advancing to re-measure the yarn; and Fig. 4 is a diagrammatic view showing a fragment of knitted fabric to illustrate particularly the inner selvage edge formed by a reinforcing or splicing yarn.

Applicant's invention is illustrated in the drawing as applied to a flat full-fashioned hosiery machine of ordinary description, which comprises a series of supporting frames such as that indicated at 10 in Fig. 1, connected by a lower front rail 12, head rail 14, rear base rail 16, and the usual work table 18 running along the length of the machine. Supported on the head rail 14 is the usual sinker bed 20. The knitting instrumentalities of the machine include spring beard 55

needles 22 supported on a needle bar 24 for vertical in-and-out movements with relation to a fixed press edge 26 formed on the sinker bed 20, independently movable yarn measuring sinkers 28, dividers 30 alternating with the sinkers, and knockover elements 32. The operation of the knitting elements above described including particularly the sinkers, needles and dividers, is controlled from a main cam shaft 34 of the machine through operating connections (not shown) which may be of any ordinary description well known in this art.

The machine is provided with the usual yarn feeding and controlling devices including carriers such as those shown at 40 and 42 in Fig. 2, supported to move lengthwise of the machine for laying yarn along the needle series in position to be engaged in the throats of the sinkers 28. As shown in Fig. 2, the carrier 40 is feeding a main knitting yarn to the needles while the carrier 42 is utilized for feeding a reinforcing yarn over a portion only of the needle series. The yarn associated with each yarn carrier is drawn from a source of supply (not shown), passing around suitable guiding, tensioning and take-up devices which may be of ordinary description, to the yarn carriers 40 and 42.

The knockover elements 32 as shown in Fig. 1 of the drawing, are rigidly supported on a knock-over element bar 50 secured to a frame 52 which is supported to slide vertically in guideways formed on the front face of the head rail 14. Vertical positioning movements are imparted to the frame 52 and knockover elements 32 by means of lever arms 54 which engage beneath the frame 52 and are secured to a rock shaft 56. The position of the rock shaft 56 is controlled by means of a knockover bit cam lever 58 secured thereto, and having mounted thereon a cam 40 roller 60 which is laterally shiftable on pivot pin 62 to ride alternatively against the regular knock-over bit cam 64, or a special knockover bit cam 66 more fully to be described, rigidly secured adjacent the cam 64 on the main cam shaft 34. The frame 52 is maintained at all times in engaging contact with the supporting levers 54 by means of small tension springs such as that indicated at 68 connected between the frame and the supporting levers. The cam lever 58 and roller 60 are tensioned downwardly against the cam 64 or 66 by means of a heavy tension spring 70 connected to the forward end of the cam lever, this downward movement being limited by the engagement of an arm 72 on the lever with a shaft 74 on which the forward and back needle motion cam lever is fulcrumed. The roller 60 may be shifted to render either of the cams 64 or 66 operative to control the operation of the knockover bits through mechanism of ordinary description comprising a shifting fork 76 which engages the roller 60, and is secured to a longitudinally movable shift rod 78 extending lengthwise of the machine. The position of the shift rod 78 may be controlled manually or automatically from the usual pattern chain of the machine as desired.

It is the usual practice in machines of this description, to maintain the knockover elements and fabric supported thereon normally in a relatively low position to avoid catching the noses of the advancing sinkers in the previously knitted fabric, and thereafter to raise the knockover bits to a point immediately beneath the sinkers only as the needles are moved forwardly and down from the press position to draw the newly kinked

yarn off of the noses of the sinkers 28 and dividers 30, so that the distance through which the kinks must be moved unsupported between the sinker noses and the knockover elements, is reduced to a minimum. The knockover bit cam 64 has formed thereon a rise indicated in dotted lines at 84 which acts against the cam roller 60 to raise and to maintain the knockover bits in their extreme high position as the newly formed kinks of yarn are drawn off the sinker noses during the movement of the needles to the knockover.

In accordance with a principal feature of the present invention, a special knockover bit cam 66 is provided which is rendered operative to control the operation of the knockover bits by the shifting of the roller 60, and is intended for use particularly during the knitting of partial courses with a reinforcing or splicing yarn. The special knockover bit cam 66 has formed thereon a rise 88 which acts against the cam roller 60 to raise the knockover bits 32 to their high position at an earlier stage in the knitting cycle than would normally be the case, that is to say, after the sinkers 28 have been advanced, but prior to the advance of the alternating dividers 38. The previously knitted fabric is now supported, as best shown in Fig. 3, at a level which is closely adjacent the under face of the sinkers, but still leaves a sufficient amount of clearance between the sinkers and knockover bits to prevent interference of the dividers with the fabric which is held down at this time by the fully advanced sinkers. The dividers are now advanced to re-measure the yarn against the needle shanks as shown in Fig. 3, and the needles following their usual mode of operation, are moved rearwardly and down to the press, and then forwardly while the sinkers and dividers are retracted to cause the newly formed kinks to be drawn off of the noses of the sinker and divider elements.

The effect of the upward movement of the knockover bits 32 prior to the advance of the dividers 30, is to effectively reduce the length of the selvage loop formed on the last active needle by the knitting yarn, and thereby to secure a tighter selvage edge than that produced by the normal operation of the cooperating sinker, divider, knockover and needle elements in machines of this general type.

The manner in which the raising of the knock-over bits 32 prior to the advance of the divider elements 30 operates to produce a shorter selvage loop, will be readily understood in connection with Figs. 2 and 3 of the drawing, which illustrate somewhat diagrammatically the positions of a feeding yarn and previously knitted fabric with relation to a needle knitting a left hand selvage on a knitting section. It may be assumed that the sectional views Figs. 2 and 3, illustrate the operation of a needle forming an inner selvage. In accordance with the usual practice, the yarn carrier 42 having moved to the left a sufficient distance to cause the selvage needle 22 to form the selvage loop of the previous course, has now been returned to its extreme limit to the right, and the sinkers 28 have been advanced between alternate needles to measure yarn. The position of the parts at this point in the knitting cycle is illustrated in Fig. 2. With the usual construction and mode of operation of flat full-fashioned knitting machines of this general description, a divider 30 will always be interposed between the active needle forming an inner selvage edge and the adjacent active needle. This is true because a sinker element 28 must always be interposed

between the yarn carrier 42 and the last active or selvage needle 22 to cause the selvage needle to take yarn.

After the sinkers 28 have been advanced to measure the yarn, but before the dividers are advanced, the knockover bits 32 are now raised to the high position shown in Fig. 3, by the engagement of the knockover bit cam roller 60 with the rise 88 of the knockover bit cam 66, thus considerably reducing the distance covered by the length of yarn extending from the fabric to the first active or selvage needle 22, and causing this yarn to be slackened off. The dividers are now advanced following the usual mode of operation, causing a sufficient amount of yarn to be robbed from the kinks formed by the sinkers, to re-measure and to kink the yarn against the shanks of all the needles. During this re-measuring operation, the divider 30 adjacent the selvage needle, will take up the excess yarn provided by the raising of the knockover bits 32 and fabric supported thereon, before any yarn is robbed from the first active sinker 28 standing between the second and third active needles. The needle yarn kink formed against the first active needle is thus reduced in length by the amount which the fabric has been raised, so that a relatively shorter selvage needle loop is formed than would be the case where the knockover bits 30 are retained in their normal low position shown in Fig. 2. It will, of course, be understood that the raising of the knockover bits 32 as above described, to form an inner selvage edge of a reinforcing yarn, will have no effect upon the length of the wale loops formed by the needle 22 upon which the inner selvage reinforcing yarn loops are superimposed, inasmuch as these wale loops of the main feeding yarn are not during the yarn sinking operation directly connected to the fabric, and may therefore be acted upon by the sinkers and dividers in the usual manner. During the subsequent progress of the knitting cycle, the needles are moved downwardly and rearwardly to press, and then forwardly, the sinkers 28 and dividers 30 being simultaneously withdrawn so that the finished yarn kink may be drawn off of the sinker noses onto the knockover elements which are maintained in their high position so that this operation may be performed in the usual manner.

A principal advantage of the relatively shorter inner selvage wale loops of reinforcing yarn produced as above described, consists in the fact that these loops, and more particularly the yarn forming the outer or connecting leg of the selvage, is drawn tightly into the body of the fabric instead of being loosely knitted therein as would normally be the case, so that the reinforcing yarn will present an inner selvage edge which is neat in appearance even when these loops appear on the outside of the fabric as, for instance, in the knitting of inside-out hosiery. The formation of the inner selvage loops in the manner above described, has the further advantage that a straight, finely drawn line of demarcation is secured between the reinforced and adjacent non-reinforced portions of the blank which tends to improve the appearance of the reinforced por-

tions of the blank, even when the reinforcing threads appear on the outside of the fabric.

It will be understood that the invention is not limited to the specific embodiment shown, and that various deviations may be made therefrom without departing from the spirit and scope of the appended claims.

What is claimed is:

1. In a flat knitting machine having needles movable as a unit with relation to a press edge, independently movable yarn measuring sinkers to which the yarn is fed and dividers, the combination of knockover elements cooperating therewith, and a knockover bit motion including a cam operable to raise the knockover bits from a low position to a point closely adjacent the underside of the sinkers subsequent to the advance of the sinkers to sink yarn and prior to the advance of the dividers to reform the yarn kinks against the shanks of all the needles.

2. In a flat knitting machine having needles movable as a unit with relation to a press edge, independently movable yarn measuring sinkers to which the yarn is fed and dividers, the combination of knockover elements cooperating therewith, and a knockover bit motion including a knock-over bit cam adapted for raising the knockover bits from a low yarn sinking position only to receive and to knock over the newly formed course of yarn, an additional knockover bit cam operable to raise the knockover bits from their low to their high position subsequent to the yarn sinking and prior to the dividing operation, and control means shiftable to connect one or the other of said cams to move the knockover bits.

3. In a flat knitting machine having needles movable as a unit with relation to a press edge, independently movable yarn measuring sinkers to which the yarn is fed and dividers, the combination of knockover elements cooperating therewith, and a knockover bit motion including a knock-over bit cam adapted for raising the knockover bits from a low yarn sinking position only to receive and to knock over the newly formed course of yarn, an additional knockover bit cam operable to raise the knockover bits from their low to their high position subsequent to the yarn sinking and prior to the dividing operation, a cam lever, a cam follower, and a control element for shifting said follower to engage alternatively with one or the other of said cams.

4. The method of knitting inner selvage edges with a reinforcing yarn on a flat knitting machine having needles movable as a unit, independently movable yarn measuring sinkers, dividers and knockover bits which comprises advancing the sinkers to measure yarn, raising the knockover bits and fabric supported thereby to a high position adjacent the underside of the sinkers subsequent to the yarn sinking operation to permit the subsequent shortening of the leg of the selvage needle wale loop connected to the previously knitted fabric by the action of the dividers, and thereafter advancing the dividers to re-measure the yarn against the shanks of all the needles.

JOHN S. CHIPMAN.
